UNITED STATES PATENT OFFICE

2,636,661

EGG CARTON

John W. Cox, Chicago, Ill., assignor to Shellmar Products Corporation, Chicago, Ill., a corporation of Delaware

Application April 15, 1949, Serial No. 87,789

5 Claims. (Cl. 229—28)

1

The present invention pertains to improvements in foldable, cellular paperboard egg cartons of the general type shown in Troyk Patent No. 1,783,397. The Troyk carton has received wide acceptance in the trade, but occasional instances of carton failure and resultant egg loss occur, usually by crushing under vertical load.

Accordingly, it is a general object of the present invention to provide a foldable paperboard, cell type egg carton of improved structure to increase the strength of the carton, to improve its protection for eggs, and to facilitate the setting-up operation by which the cells are locked into the inside of a cushion-forming bottom.

Another object is to provide such a paperboard egg carton characterized by a novel relationship of its cell-defining cross partitions to a bottom and longitudinal partition-forming structure, whereby the erected cross partitions are held against shifting in a direction longitudinally of the carton and are braced to effectively oppose vertical buckling.

A more specific object of the invention is to provide a paperboard carton including a section which forms a bottom, and a plurality of cross partitions hinged to the front and rear walls of the carton, which partitions are insertable in the bottom section, characterized by the feature of providing the bottom section with pre-formed, partition-receiving slits and with creases serving to afford yieldable flaps or tabs adapted to constitute a stop engageable with the cross partitions disposed in the slits.

It is a still more specific object to provide a carton of the type referred to in the preceding paragraph wherein the tabs are disposed on both sides of the cross partitions and are so formed and related to the cross partitions and to one another that in operative position they engage the partitions in a vertically spaced relation, thereby constituting a force couple acting to brace the partition.

Another object is the provision of a carton of the type described having a wall structure marginally cut out between the spaced bottom and partition sections to facilitate opening the latter for mutual interlock.

Generally considered, it is an object of the invention to provide a paperboard egg carton of the foldable partition type, in which the grain of the paperboard stock characteristically runs in a vertical crosswise direction across the front and rear walls of the carton and in a horizontal crosswise direction across the erected cross partitions, and in which carton the cross partitions

5 are so interengaged with, sustained and braced by the carton bottom as to effectively resist a tendency to buckle about an axis paralleling their direction of grain, thereby greatly rigidifying, stiffening and strengthening the carton as a whole.

The foregoing statements are indicative in a general way of the nature of the invention, but other and more specific objects will be apparent 10 upon a full understanding of the construction and operation of the device.

Several embodiments of the invention are presented herein for purpose of illustration, and it will be appreciated that the invention is susceptible of incorporation in still other modified forms coming equally within the scope of the appended claims.

In the drawings,

Fig. 1 is a plan view of the flexible paperboard 20 blank from which one embodiment of the carton of the present invention is constructed;

Fig. 1A is a fragmentary plan view, partially broken away, showing the carton in assembled glued condition, prior to being erected to egg receiving form;

Fig. 2 is a top plan view of the open carton according to the invention, illustrating the relationship of certain flexible flaps or tabs in the bottom section of the carton to brace the cross partitions of said carton in the operative, erected or upright position of said partitions;

Fig. 3 is a somewhat enlarged fragmentary view in longitudinal, vertical section along a line generally corresponding to line 3—3 of Fig. 2, more 35 clearly illustrating the bracing and stiffening interaction of the aforesaid flap or tab elements with the cross partitions;

Figs. 4 and 5 are views in vertical transverse section along lines generally corresponding to 40 lines 4—4 and 5—5, respectively, of Fig. 3, further illustrating the relative positions of the cross partitions and the bottom and longitudinal partition forming section of the carton when the latter is erected; and

Figs. 6 and 7 are fragmentary plan views representing alternative, somewhat modified arrangements of cutting and creasing of a blank to produce the interlocked and braced longitudinal cross partition structure of the present invention.

Fig. 1 illustrates a flat paperboard blank which 50 resembles closely the blanks illustrated in the Troyk patent. It includes a bottom and longitudinal partition forming section 10, which is subdivided by a medial, longitudinally extending crease 11 into equal, complementary panels 12,

13. These panels are in turn conjoined respectively by parallel longitudinal creases 14, 15 to a rear wall 16 and a front wall 17. The rear wall is hingedly connected by crease 18 to a cover panel or section 19 which has a conventional hook-carrying locking flap 20 connected thereto by longitudinal crease 21.

A cross partition section 22 is hinged to front wall 17 by the series of longitudinally aligned creases 23, and the cross partition section is 10 hinged by aligned creases 23 on its opposite margin to a narrow glue flap 24. The section 22 is further slitted and cut to provide a plurality of identical forked cross partitions 25, which partitions are individually swingable about transversely aligned pairs of crease lines 26 from a coplanar relationship, shown in Fig. 1, to their operative, erected, and upright position parallel to one another. The small triangular webs 27 defined by creases 23, 28 serve to connect the cross partitions to the front and rear walls 17, 16, respectively, when the glue flap 24 is adhered to the latter. As assembled in knock-down form, the cross partitions 25 are folded on themselves about the medial, longitudinally extending creases 25'.

The bottom and longitudinal partition-forming section 10 is provided with a longitudinally spaced series of transverse slots 28, one for each cross partition 25, which slots are aligned with the cross partition hinges 26 and extend equidistantly on either side of the medial crease line 11. These slots receive the forked portion of the cross partitions 25 when the carton is in erected condition, as illustrated in Figs. 2-6. The panels 12, 13 on either side of the crease line 11 are provided with intersecting slits 29 in order to cushion eggs deposited in the cells between cross partitions 25.

Referring to Fig. 1, the bottom section 10 is provided with two parallel rows of slitted and creased partition-bracing formations generally designated 30. These formations are disposed in pairs which are laterally aligned with the pairs of cross-partition hinge lines 26, being located at equal distances from crease 11. They are intended for the reception of cross partitions 25 and for bracing, the latter when the cross partitions are swung to upright position and inserted through the carton bottom. So engaged, the cross partitions are held against longitudinal movement and are strengthened to resist vertical buckling under load. As a result, the carton as a whole is materially strengthened and rigidified by the improved column action of the partitions. Moreover, the walls 16 and 17 are rendered highly resistant to collapse by reason of their integral connection to the partitions. This may be accounted for by the fact that the cross partition, resting on a supporting surface, exerts a wall suspending action at the hinge webs 21. In any event, the walls 16, 17 are enabled to maintain their original position under vertical loads which, in ordinary Troyk carton structures or other types of cartons, would cause marked outward bulge or buckling thereof.

In a preferred embodiment, the formations 30 each comprise a somewhat elongated slit 31 extending transversely of the bottom and partition-forming section 10, each slit being intersected at its opposite ends by the angular, longitudinally aligned V-slits 32. The slit 31 is preferably disposed to one side of a theoretical line through the apices of the V-slits 32, i.e., on the forward or left-hand side in Figs. 1-3, or in the direction

from which the partitions 25 are swung to upright position. The reason for this particular relationship will appear hereinafter. Thus flexible flaps 33, 34 are defined on either side of slit 31, the flap 34 being of somewhat larger area than flap 33 because of the off-centering of slit 31. The flap 34 also is rendered substantially more flexible with relation to the panel 12 or 13 in which it is disposed, as by scoring 35 connecting the ends of slits 32. Flap 33 is not similarly scored.

The above features result in the provision of end-narrowed openings 36 (see Fig. 3) to receive the lower portion of the cross partitions 25. The latter are interlockingly engaged with bottom section 10 by the mutually in-turned hooks or shoulders 37 on their lower forked leg portions. Openings 36 are of course normally closed by the flaps or tabs 33, 34.

In assembling the carton from the above described blank, the latter is successively folded on itself along crease lines 25' and 11 and the glue flap 24 is adhered to the rear wall 16, in accordance with the conventional procedure. This places the carton in its flat, knocked-down condition for shipment or storage.

In the collapsed carton, as shown in Fig. 1A, the rear one-half of the cross partition section and the rear one-half of the bottom section are 30 spaced apart by a portion of the rear wall 16. The rear wall is marginally cut away at 39 at a point between the cross partition section and the cuts 31, 34 of the bottom section. In erecting the carton, it is placed with its back side 35 down and held in such position by restraining the cover section 19. The front wall is engaged opposite the cut-out 39 and lifted upwardly to initiate spreading the walls apart at the end of the carton. The spreading action then is progressed the length of the carton to present the partitions and bottom section in upright position so that the bottom may be pushed in and engaged with the partitions when the latter are rotated into cross position.

The carton is erected by causing the front and rear walls 16, 17, the bottom and longitudinal partition section 10, and cross partition panel 22 to assume a generally rectangular outline. The cross partitions 25 are then swung to the operative upright position illustrated in Figs. 2 through 5, the bottom section 10 is bent upwardly along medial crease 11 to define the two-walled longitudinal partition of the carton, designated 38, and the cross partitions are interlocked in the openings 36 adjoining the formations 30 of section 10 by means of the inturned cross partition hook elements 37. The cross partitions are guided into the openings 36 and are positioned properly in a plane extending between the apices of V-slits 32 by the opposed angled or V-shaped margins of the openings 36. Additional guiding action is performed by the flaps 33, 34. As the ends of the cross partitions hit the trap doors 33 and 34 during the locking operation, these doors 60 are deflected outwardly, thereby deflecting the partitions toward the center of the openings 36 65 in case the partitions are slightly out of alignment.

The particular arrangement and configuration 70 of the cross partition-receiving formations 30 cause the respective flaps 33, 34 thereof to be deflected differently when the cross partitions are inserted therein. Inasmuch as the rearward flap 34 has a greater degree of flexibility than flap 33, it naturally is displaced farther down-

ward than the flap 33, as shown in Figs. 3 and 4. The flap 33 usually assumes a position fairly closely adjacent the plane of the adjacent bottom section area and the flap 34 is bent substantially farther down. Though their exact individual disposition will naturally vary, the two flaps generally assume positions which are in substantially vertically spaced relation to one another (see Fig. 3) on opposite sides of partition 25.

In the preferred form, the rear flap, i. e., that located on the side of the slit 31 toward which the cross partition swings, engages the partition well below the other flap, and the two flaps have direct frictional engagement with said partition at two points to brace the same. Bending the cross partitions into erect position about the hinges 26 causes the partitions to tend to bulge outwardly in resisting the bend, thereby reducing their vertical rigidity. The trap-door 34 braces the outer end of each partition, and the trap-door 33 pushes the partition inwardly on the side of the partition toward which the partition tends to bulge. Accordingly, the cross partition is effectively braced in vertical position to present maximum column strength. Its lower edges lie approximately in the horizontal plane of the bottom margins of walls 16, 17, so as to rest on a supporting surface, and its upper extremity is abutted by the cover 19; hence, it coacts positively with and tends to support the walls in resisting crushing forces on the carton. Due to their integral connection with said walls and their engagement with a supporting surface, the cross partitions exert a pronounced vertical suspending and reinforcing action on the front and rear walls, substantially increasing their resistance to buckling under vertical compression.

The bracing of the cross partitions 25 by flaps 33, 34 also has the function of offsetting a tendency to vertical buckling which arises because of the normal direction of grain of the paperboard stock. Inasmuch as the grain extends transversely of the blank, i. e., in the direction of the double headed arrows shown in Fig. 1, it follows that, when the cross partitions 25 are swung downwardly to operative, upright position, the grain thereof runs horizontally (see the arrows in Figs. 4 and 5). The tendency of the cross partitions to bulge laterally or buckle is thus normally aggravated by the horizontal disposition of their grain structure. However, in the present carton a force couple is exerted on the partition to substantially stiffen the latter vertically. Moreover, the direct engagement of the flaps or bottom section edges with the opposite sides of the cross partition in effect reduces the height of the cross partition which is subject to bulging. Still further, due to the fact that the above described formations 30 are formed in the upwardly convergent panels 12, 13 of the bottom and longitudinal partition section 10, it follows that the engagement of the cross partition by the flaps 33, 34 is along a line extending upwardly and inwardly of the carton, i. e., diagonally of the grain of the cross partitions. This still further extends the stiffening and buckle resisting effect of the provisions described.

As mentioned above, it is desirable in the erection of the carton to deflect the rearmost flaps 34 farther downwardly than the flaps 33. The embodiment of Figs. 1 to 5 inclusive relates to a type of formation which has this function. The same result may be accomplished by an appro-

priate adjustment in the timing of the carton set-up machine which is usually employed for the purpose of automatically erecting structures of this type to produce deflection of the bracing flaps in different degree. Other embodiments of the invention are shown in Figs. 6 and 7.

The embodiment of Fig. 6 is generally similar in structure and function to that of Figs. 1 to 5 inclusive. In this case, the formation 40 includes a left-hand flap structure in the form of a plurality of small flexible tongues 41 outlined by parallel cuts 42 terminating at the medial slit 43. The other flap 44 is similar to the flap 34 and the slit 43 joins the opposed V-shaped slits 45 on the forward side of the apex thereof.

In the modification of Fig. 7 a single transverse slit 48 is caused to intersect the termini of a pair of opposed angled cuts 49 immediately to one side of the opposite apices of said cuts. This defines a single flap 50 hinged by a crease line 51 to the bottom structure and adapted to engage and brace a cross partition at a depressed point relative to the remainder of the bottom panel of the carton.

Those skilled in the art will readily perceive the feasibility or desirability of various further alterations and modifications of the above described concept, without departing from the principles of the invention. The invention accomplishes a substantial reinforcement and rigidification of a partitioned cell type carton, as a whole, by the direct side bracing and confinement of its constituent partitions at their points of penetration of the carton bottom, accomplished by a force couple. I therefore desire that the invention be construed in this light, and no more limitedly than is reasonably consistent with the language of the appended claims.

I claim:

1. A paperboard egg carton comprising front and rear walls integrally connected by a bottom section having a plurality of slits between said front and rear walls, said slits including straight portions extending transversely of said bottom section and longitudinal portions extending from the opposite termini of said straight portions, and transversely extending cross partitions disposed, in the erected condition of the carton, in upright position relative to said bottom section, said cross partitions being hingedly connected to said front and rear walls and the lower portions thereof penetrating the slits in said bottom section when in said upright position, an edge of the material defined by one of said slits being adapted for engagement with a side of one of said cross partitions in a direction normal to its plane and a plane different from that of said penetrated section, the material of said bottom section being of differing flexibility on opposite sides of said transverse slits, whereby to engage said cross partitions at different vertical levels, the lower extremities of said cross partitions being substantially coplanar with the lower margins of said walls to sustain the latter through the hinged wall and partition connections when the carton rests on a supporting surface, the engagement of said cross partitions in different vertical planes by said bottom section providing a force couple resisting horizontal buckling of said cross partitions under vertical compressive load transmitted through the latter.

2. A collapsible paperboard egg carton comprising front and rear walls integrally and marginally connected by a bottom section, said bottom section being provided between said front

and rear wall marginal connections thereof with transverse slits, each of which is bordered on at least one side thereof by a flexible flap formation, said slits including straight portions extending transversely of said bottom section and longitudinal portions extending from the opposite termini of said straight portions, and transversely extending cross partitions disposed, in the erected condition of the carton, in upright position relative to said walls and bottom section, said cross partitions each being hingedly connected to said front and rear walls and the lower portions of said cross partitions penetrating said bottom section slits, said respective cross partitions being positively engaged and braced by the adjacent edge of said respective flap formations, said flap formations being displaced from the plane of said bottom section when so engaged, the material of said bottom section being of differing flexibility on opposite sides of said transverse slits, whereby to engage said cross partitions at different vertical levels, the lower extremities of said cross partitions being substantially coplanar with the lower margins of said walls to sustain the latter through the hinged wall and partition connections when the carton rests on a supporting surface, the engagement of said respective cross partitions in different vertical planes by said bottom section and flap formations thereof providing a force couple resisting horizontal buckling of said cross partitions under vertical compressive load transmitted through the latter.

3. A paperboard egg carton comprising front and rear walls integrally connected adjacent their lower margins by a bottom section, said bottom section being provided between said front and rear wall marginal connections thereof with transverse slits, each of which is defined by a set of opposed flexible flap formations, said slits including straight portions extending transversely of said bottom section and longitudinal portions extending from the opposite termini of said straight portions, and transversely extending cross partitions disposed, in the erected condition of the carton, in upright position relative to said bottom section, said cross partitions each being hingedly connected to the said front and rear walls and the lower portions of said cross partitions penetrating a substantial distance through said bottom section slits, said cross partitions being positively engaged and braced by adjacent edges of said flap formations and one of said formations of each set being deflected downwardly by its respective cross partition to a greater extent than the other, the material of said bottom section being of differing flexibility on opposite sides of said transverse slits, whereby to engage said cross partitions at different vertical levels, the lower extremities of said cross partitions being substantially coplanar with the lower margins of said walls to sustain the latter through the hinged wall, engagement of said cross partitions in different vertical planes by said respective adjacent flap formations providing a force couple resisting horizontal buckling of said cross partitions under vertical compressive load transmitted through the latter.

4. A collapsible paperboard egg carton comprising front and rear walls, a bottom connecting said walls and including inwardly and upwardly convergent, longitudinal partition sections, and cross partitions hinged to said walls adjacent the upper margin thereof for swinging movement to an upright position, said bottom being provided

with pairs of aligned, transverse slits, each of which slits is substantially joined at its ends by further slits at an acute angle thereto to define a cross partition receiving opening having a flexible trap door flap formation on at least one side thereof, said respective cross partitions being progressively guided by said acute angled flap formations toward and into said openings and when so positioned being positively engaged and braced by said formations above the lower free margins thereof, the material of said bottom section being of differing flexibility on opposite sides of said transverse slits, whereby to engage said cross partitions at different vertical levels, the extremities of said lower free margins lying substantially coplanar with the lower margins of said walls to sustain the latter through the hinged wall and partition connections when the carton rests on a supporting surface, said respective flap formations engaging said respective cross partitions along lines in vertically spaced relation to lines of engagement of the opposite side thereof by the remainder of the bottom, and providing a force couple at said respective lines of engagement resisting horizontal buckling of said cross partitions under vertical load transmitted through the latter.

5. A collapsible paperboard egg carton comprising front and rear walls, a bottom connecting said walls and including inwardly and upwardly convergent, longitudinal partition sections, and cross partitions hinged to said walls adjacent the upper margin thereof for swinging movement to an upright position, said bottom being provided with pairs of aligned, transverse slits, each of which slits is substantially joined at its ends by further slits at an acute angle thereto to define a cross partition receiving opening having a flexible trap door flap formation on each side thereof, said cross partitions being progressively guided by said acute angled flap formations toward and into said openings and when so positioned being positively engaged and braced by said formations above the lower free margins thereof, one of said flap formations being more flexible than the other whereby said formations assume a vertically spaced relation when operatively engaged with a cross partition, the material of said bottom section being of differing flexibility on opposite sides of said transverse slits, whereby to engage said cross partitions at different vertical levels, the extremities of said lower free margins lying substantially coplanar with the lower margins of said walls to sustain the latter through the hinged wall and partition connections when the carton rests on a supporting surface, engagement of said cross partitions at different vertical elevations by said respective flap formations providing a force couple resisting horizontal buckling of said cross partitions under vertical compressive load transmitted through the latter.
